UNIVERSAL MECHANO-SURGICAL APPARATUS

Nicolas Leuchter, Montreal, Quebec, Canada, assignor of one-third to Rodolphe Lallemand and one-third to Pierre Z. Rheaume, both of Montreal, Quebec, Canada

Application August 1, 1935, Serial No. 34,121

2 Claims. (Cl. 128—25)

The present invention relates to exercising machines of the type called mechano-surgical.

An important object of the invention is the provision of a machine having a variety of exercising appliances which is compact and portable.

Another object of the invention is the provision of a machine of the above character embodying a relatively large number of bending and vibratory appliances for exercising various parts of the human body.

A further object of the invention is the provision of a machine of the aforesaid character carrying an actuating motor and designed so as to be easily moved from place to place.

Still another object of the invention is the provision of a machine of the above character having efficient motor actuated foot bending apparatus for exercising the ankles.

A still further object of the invention is the provision of a machine of the above type having motor actuated leg bending means for exercising the knees.

Still another object of the invention is the provision of a machine of the above character having body bending appliances.

Other objects and advantages of the invention will become apparent as the description progresses.

In the accompanying drawings forming a part of this specification and in which like reference characters are employed to designate corresponding parts throughout the same:

Figure 1 is a perspective view of the assembled machine,

Figure 2 is a side elevational view of the same, Figure 3 is a vertical section through the upper portion of the machine,

Figure 4 is a fragmentary top plan view of the machine, partly broken away,

Figure 5 is a longitudinal section through a leg supported structure taken on the line 5—5 of Figure 4,

Figure 6 is an end elevational view of the same, Figure 7 is a transverse section on the line 1—7 of Figure 5,

Figure 8 is a fragmentary section on the line 8—8 of Figure 3,

Figure 9 is an enlarged fragmentary section taken at line 9—9 of Figure 4,

Figure 10 is an enlarged section taken on the line 10—10 of Figure 1,

Figure 11 is a fragmentary side elevational view showing the rotary arm exercising appliance,

Figure 12 is a section taken on the line 12—12 of Figure 2,

Figure 13 is an end view of a foot bending apparatus,

Figure 14 is a vertical section through one end of the machine,

Figure 15 is an enlarged transverse section taken on the line 15—15 of Figure 2, and

Figure 16 is an enlarged side elevational view of a knuckle vibrator.

Referring to the drawings, wherein for the purpose of illustration is shown a preferred embodiment of the invention, A generally designates the frame of the machine embodying a horizontal platform 20 secured on four corner standards 21. Adjacent the lower ends the standards 21 are braced by horizontally disposed bars 22. To the lower end of each standard 21 is secured a swivel bracket 23 in which is rotatably mounted a carrier wheel 24, enabling convenient movement of the machine from place to place.

On a horizontal cross structure below the platform is secured a drive motor 26 having a horizontally extending shaft 27 formed at the outer end with a crank 28. At the intermediate portion of the drive shaft 27 is fixed a grooved pulley wheel 29. Above the motor is journaled a horizontal countershaft 30 having grooved pulley wheels 31, 32 and 33 fixed thereon. At one side of the countershaft 30 is journaled a horizontal auxiliary shaft 34 having a grooved pulley wheel 35 fixed adjacent one end and having an eccentric disc 36 fixed on the intermediate portion thereof. At the outer end of the shaft 34 is secured a slide bracket 37 provided with a set screw adapted to adjustably hold in position a crank bar 38 slidably fitted in the bracket 37. At one end of the crank bar 38 is rotatably secured a horizontally disposed handle 39.

At one side of the frame is journaled a vertical double grooved transmission wheel 41 driven through the medium of a belt 42 trained over one groove in the periphery of this wheel and the grooved pulley wheel 33 on the countershaft. A belt 43 is trained over the relatively large pulley wheel 32 on the countershaft and the reduced pulley wheel 29 on the drive shaft to effect the driving connection between the motor shaft and the countershaft. A belt 44 is trained over the relatively large wheel 35 of the shaft 34 and over the small pulley wheel 31 on the counter shaft.

In a pedestal bearing on the platform 20 at one side of the frame is journaled a vertically disposed drive wheel 46 arranged above the transmission wheel 41 and driven by a belt 47 trained over these wheels. To the outer side of the wheel

50

55

46 is rigidly secured a diametrically disposed bar 48 having slidably fitted thereon a sleeve 49. Upon a stem extending horizontally outward from the sleeve 49 is supported a rotary gripping handle 50 adapted to be grasped by one hand of a patient receiving treatment for exercising the wrist and elbow. The fastening stem, indicated at 51, is threaded in the sleeve so that the latter may be secured in selected position on the bar 10 48 which is preferably formed with a graduated scale to designate various positions thereon. An arm rest 52, shown at Figure 11, and in dotted lines at Figure 1, may be removably connected with a bracket 53 on the frame so that the gripping handle 50 may be engaged to revolve the hand for exercising the wrist or for exercising the elbow or shoulder.

To the pin of the crank 28 is connected the lower end of a vertical rod 55 extending through 20 an opening in the platform 20 and having its upper end pivotally connected with a horizontally disposed lever 56. On one end of the lever 56 is secured a padding sleeve 57 arranged adjacent 15 an arm rest 58 on the platform. The opposite 25 end of the lever 56 is pivotally connected to an upstanding bar 59 having its lower end connected to a pivot bracket 60. On the bar 59 is slidably disposed a cross fitting 61 which may be secured in desired position by means of a screw 62. Projecting horizontally outward from the fitting 61 is 30 a coiled spring extension 63 providing a resilient support for a padded ball 64 attached to the end and adapted to function as a knuckle vibrator. To the rod 55 is connected an angular bracket 65 35 embodying a vertically disposed depending support bar 66 carrying thereon an elongated channel-shaped holder 67 slidably engaging the bar and adapted to be fastened in selected position by a set screw 68. The holder channel 67 carries 40 thereon a corrugated pad 69 formed of rubber or the like and designed to provide an element for vibrating or striking lightly the back and spine of a patient. To the lower portion of the bar 66 is adjustably connected a bracket 70 45 formed with a U-shaped extension 71 and designed for treating the thigh and calf.

To one side edge of the platform 20 are secured 50 a pair of parallel angularly depending bars 73 provided with transversely opposed apertures disposed to receive therein a pivot pin 74. The pin 74 is slidable through a pair of pivot brackets 75 secured to the outer side of a foot board 76. At 55 one side of the foot board is mounted a segmental graduated scale 77 for a purpose which will be described hereinafter. Formed integral with and depending from the lower edge of the foot board 76 is a slotted member 78 disposed to engage an actuating pin 79. The pin 79 may be removably fitted in any one of a number of longitudinally 60 spaced apertures 80 formed in a rocker bar 81 which is rockable on a supporting shaft 82 attached to the frame. The inner end of the rocker bar is formed with a slotted extension 83 arranged to engage diametrically opposed edge portions 65 of the eccentric disc 36. Thus, revolution of the disc oscillates the rocker bar and causes swinging movement of the foot board 76. The arcuate movement of the foot board may be regulated by varying the position of the pin 79 on 70 the rocker bar 81, the movement of the foot board being readily ascertained by the scale 77. Thus, a patient seated on the platform, as shown at Figure 2, places his feet against the foot board 76 so that swinging movement of the board will 75 result in a beneficial exercise of the ankles.

To a side edge of the platform is hingedly connected an inclined outwardly projecting elongated leg support 85 having slidably fitted thereon a foot rest 86. To the underside of the foot rest 86 is connected a bracket 87 threadedly engaging 5 a longitudinally disposed screw 88 rotatable by a hand crank 89 to adjust position of the foot rest. Adjacent the upper portion of the leg support 85 is mounted a segmental graduated scale 90 disposed to indicate the swinging movement of 10 the support.

To a web 92 formed on the pulley wheel 35 adjacent the periphery thereof is connected a laterally projecting threaded pivot member 93 formed at one end with a knurled head and supporting a sleeve 94 rotatable thereon. To the inner end of the sleeve is connected a cap 95 serrated at the edge and disposed to engage the serrated edge portion of an annular member 96. To the outer end portion of the sleeve 94 is connected a crank arm 97 on which is slidably fitted a sleeve 98. As will be noted, the crank 97 together with the sleeve 94 may be rotatably adjusted relative to the wheel 35 by loosening the pin 93 and rotating the serrated cap 95 relative 25 to the fixed serrated member 96. A pivot pin 99 is connected to and extends laterally from the sliding sleeve 98. One end of a telescopic connecting rod 100 is pivotally connected to a bracket 101 secured to the lower end of the leg support 30 85. The opposite end of this rod is pivotally connected with the pivot pin 99.

A second connecting rod 102 is mounted so that one end is also pivotally connected with the pivot pin 99 while the other end rotatably engages the 35 intermediate portion of a crossbar 103 adjustably fitted upon an elongated frame constituting a pair of side bars 104 projecting through a slot in the platform 20 and having a swinging connection therewith through the medium of bearing brackets 105 engaging a pivot shaft 106 attached to the platform. The upper ends of the side bars 104 project above the platform and carry thereon a transverse cross bar 107 which is mounted so as to enable longitudinal adjustment. Thus, rotary 40 operation of the wheel 35 results in similar operation of the crank arm 97 and the connecting rods 100 and 102, resulting in swinging movement of the leg support 85 for exercising the knees, and swinging movement of the frame bars 104. The 50 patient engages the upper cross bar 107 so that, during swinging movement of the bars 104, body bending and exercising action is thus effected. A removable back rest 109 is mounted on the platform to support the patient during use of the leg 55 bending and knee exercising apparatus.

At one corner of the platform 20 is secured an upstanding standard 111 supporting a curved transverse support bar 112 thereon to the ends of which are connected a pair of coiled tension 60 springs 113 having gripping handles 114 fastened to the lower end. This construction affords pulling exercises for the patient under treatment.

On the intermediate portion of the platform 20 is mounted a grip exercising appliance 116 embodying a horizontally slidably bar 117 normally urged towards one end of the device by compression springs so as to provide a resilient grip exercising appliance.

Summing up, the apparatus of the invention 70 comprises a wheeled frame, a single central source of power mounted on a sub-frame, and an upper platform on which are mounted the exercising devices. The motive power is generally the electric motor 26, although hand-power is avail- 75

able as shown at 39 in the drawings. This motor drives a plurality of shafts having eccentric cams for oscillating a number of levers. The said levers, in turn, oscillate a leg bender, an ankle exerciser, a back bender and a wrist-bending device. Both the ankle and the leg benders are arranged on one edge of the platform so that the patient may conveniently sit thereon. In all cases, the amplitude of the oscillating movement is closely adjustable so that the maximum movement permissible, in the case of crippled limbs, be consistently maintained, as well as improvements in the bending action of the treated limb. Finally, a short eccentric, directly on the motor shaft, is provided to produce a rapid vibration-like oscillation which is used for massaging the back and other limbs of the human body. All the above noted devices are passive exercisers, although active ones may be used, and are shown at 111 and 116, wherein the patient himself exercises against a given load such as provided by a spring.

Thus, it will be noted that the present machine provides a compact wheeled structure carrying a number of exercising and vibrating appliances and includes mechanism whereby several of these appliances are effectively driven by a motor carried on the frame. This construction will enable the device to be wheeled into various rooms of hospitals directly to the patient and will thus enable convenient application of kinesitherapeutic treatments.

It is to be understood that the form of my invention herein shown and described is to be taken as a preferred example of the same and that various changes as to the shape, size and arrangement of parts may be resorted to without depart-

ing from the spirit of the invention or the scope of the subjoined claims.

Having thus described my invention, I claim:

1. A mechano-surgical apparatus, comprising a frame, carrier wheels supporting said frame, a platform at the top of the frame, a leg exerciser pivoted to one side edge of the platform, means to oscillate said exerciser, an adjustable foot rest at the end of the exerciser, a downwardly inclined leg rest secured to the edge of the platform adjacent the leg exerciser, a pivoted foot plate at the outer end of the leg rest, means for oscillating the said plate, means for selectively varying the amplitude of the oscillating movement of said foot plate, bars pivoted below the platform and extending therethrough adjacent the edge opposite to that of the leg exerciser, a cross bar joining said bars, means for selectively oscillating said bars, and mechanism under the platform for operatively actuating the oscillating devices from a common power source.

2. In a mechano-surgical apparatus including a wheeled frame, the combination with a platform at the top of said frame, as a single unit, of a leg exerciser pivoted to one side of said platform, means for adjusting the effective length of said exerciser, a foot exerciser rigidly secured to the edge of the platform alongside the leg exerciser, a selectively oscillatable foot rest pivoted at the outer end of said leg exerciser, means for adjusting the foot rest fulcrum towards or away from the platform edge, an oscillatable back exerciser extending upwardly through the platform adjacent one edge thereof, a central source of motive power, eccentrics actuated by the source of power, and cranks connecting said eccentrics to the oscillatable devices recited above.

NICOLAS LEUCHTER.
